UNITED STATES PATENT OFFICE.

OTTO W. SCHAUM, OF PHILADELPHIA, PENNSYLVANIA.

DESIGN FOR A YOKE MEMBER FOR JACQUARD-LEVERS.

SPECIFICATION forming part of Design No. 33,297, dated October 2, 1900.

Application filed August 31, 1900. Serial No. 28,717. Term of patent 14 years.

To all whom it may concern:

Be it known that I, OTTO W. SCHAUM, a citizen of the United States, residing in Philadelphia, in the county of Philadelphia and State of Pennsylvania, have invented a new and original Design for a Yoke Member of a Jacquard-Lever; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In the accompanying drawings, wherein like letters of reference indicate corresponding parts, I have fully illustrated my invention.

In said drawings, Figure 1 is a top plan view of the yoke member of a jacquard-lever formed in accordance with my invention, and Fig. 2 is a view in side elevation of said yoke member.

The essential or salient feature of my design consists of a yoke member for a jacquard-lever, which comprises two lever portions, whose forward ends are bent toward each other in reverse curves, and bars, one of which connects the contiguous extremities of said lever portions and the other of which connects said lever portions adjacent the curves therein. The lever portions are des-

ignated by the reference characters a a' , the curves in said lever portions by the reference characters b b' , while the bars are respectively designated by the reference characters c and d . The lever portions a a' , each of which has the flexible curve b (or b') at one of its ends, have their other ends thickened and have projecting outwardly therefrom 40 studs e . They are flat, their cross-section being rectangular. The bar c , which connects the contiguous ends of the lever portions, is flat, being substantially rectangular in cross-section, and has formed in it two longitudinal 45 slots f . The bar d is substantially cylindrical and appears in a view in elevation of the yoke member as extending slightly beyond the sides of the lever portions, having projecting from each of its ends a reduced extension 50 or trunnion g .

Having thus fully described my invention, what I claim as new, and desire to secure by Letters Patent, is—

The design for the yoke member of a jacquard-lever, substantially as herein shown and described.

In testimony that I claim the foregoing I have hereunto set my hand this 28th day of August, 1900.

OTTO W. SCHAUM.
